UNITED STATES PATENT OFFICE.

WILLIAM B. CAMPBELL, OF GADSDEN, ALABAMA.

DISINFECTOR FOR FLUSHING-TANKS.

1,131,677.

Specification of Letters Patent. Patented Mar. 16, 1915.

Application filed January 23, 1914. Serial No. 813,932.

To all whom it may concern:

Be it known that I, WILLIAM B. CAMPBELL, a citizen of the United States, residing at Gadsden, in county of Etowah and State of Alabama, have invented certain new and useful Improvements in Disinfectors for Flushing-Tanks, of which the following is a specification.

My invention relates to an improvement in disinfectors for flushing-tanks, and the novelty of this invention resides in the arrangement whereby the after-fill is caused to discharge into a receptacle containing the disinfectant located within the tank, and thence into the bowl.

The accompanying drawing is a plan view of a flushing-tank showing the disinfectant receptacle and the after-fill tube, which seals the bowl, discharging thereinto.

T, indicates the flushing-tank; B is the ball-cock or supply valve; and O represents the over-flow pipe which may be in any of the ordinary forms, one only of many possible types being illustrated. At the upper end of this overflow pipe is located a disinfectant receptacle R, adapted to contain disinfectant and deodorizing substance, preferably in ball or tablet form, such, for instance, as mothballs, bichlorid of mercury tablets, or the like. The after-fill tube F is made to dis-

charge directly into this disinfectant receptacle, thus supplying a moderate amount of water to the latter and the balls or tablets contained therein with each flushing of the bowl. In this way, the moderate flow of the 35 after-fill gives more time for the water to become charged with the contents of the disinfectant receptacle, which would not be so marked and noticeable with a larger and more rapid flow of water.

With this arrangement, the disinfectant receptacle R is preferably located at a point 40 at or near the top of the tank, where access is easily gained by simply removing the top when it becomes necessary to replenish the 45 supply.

I claim:—

The combination with a flushing-tank having an overflow located outside thereof, and a disinfectant-receptacle located within the 50 tank at the upper end thereof, and discharging into the overflow, of an after-fill tube which discharges directly into the disinfectant-receptacle.

In testimony whereof I affix my signature, 55 in the presence of two witnesses.

WILLIAM B. CAMPBELL.
